(57) **CLAIM**

What is claimed is the ornamental design for a splice restraint, as shown and described.

DESCRIPTION

FIG. 1 is a perspective view of a splice restraint showing my new design;

FIG. 2 is a left side view of the splice restraint of FIG. 1;

FIG. 3 is a bottom view of the splice restraint of FIG. 1;

FIG. 4 is a back view of the splice restraint of FIG. 1;

FIG. 5 is a front view of the splice restraint of FIG. 1; and,

FIG. 6 is a top view of the splice restraint of FIG. 1.

The broken lines shown represent unclaimed subject matter and form no part of the claimed design.
